UNITED STATES PATENT OFFICE.

JOHN J. HASSELBACH, OF DETROIT, MICHIGAN.

RACK.

1,260,537.

Specification of Letters Patent. Patented Mar. 26, 1918.

Application filed October 23, 1916. Serial No. 127,105.

To all whom it may concern:

Be it known that I, JOHN J. HASSELBACH, a citizen of the United States, residing at Detroit, in the county of Wayne and State 5 of Michigan, have invented certain new and useful Improvements in Racks, of which the following is a specification.

This invention relates to improvements in racks and particularly to rack for filing 10 blue-prints, maps, drawings and similar flat sheets.

The objects of this invention are:

First, to provide an improved rack for 15 filing blue-prints or drawings which will permit the filing of a large number of drawings in a small space and which can be swung back against the wall when not in use.

Second, to provide a rack for filing drawings which can be constructed at a low cost 20 and which will economize the space needed for filing prints and drawings.

Third, to provide an improved rack for 25 filing drawings having a plurality of independently removable carriers so constructed that all related drawings or prints can be carried by a single carrier and removed from the rack in a group for examination without removing the other carriers or 30 drawings.

Fourth, to provide an improved rack for 35 filing drawings having a plurality of removable carriers, each carrier being so constructed as to hold a large number of prints with one of the upper corners free to permit examination of the data usually placed there without removing the prints from the carrier.

Fifth, to provide removable carriers having 40 novel clamping means, by which the sheets can be bound or secured in the carriers, said clamping means being quickly releasable.

Further objects, and objects relating to 45 economies of operation and details of construction, will definitely appear from the detailed description to follow.

I accomplish the objects of my invention 50 by the devices and means described in the following specification. My invention is clearly defined and pointed out in the appended claims.

A structure constituting a preferred em-

bodiment of my invention is illustrated in the accompanying drawings, forming a part 55 of this specification, in which:-

Figure I is a view in side elevation of a rack constructed in accordance with my invention.

Fig. II is a detail, vertical, sectional view 60 of the rack support.

Fig. III is a detail, sectional view on the line 3—3 of Fig. I.

Fig. IV is an end view of the rack with 65 the carriers removed.

Fig. V is a fragmentary view, in side elevation, of one of the carriers, the clamping means not being shown.

Fig. VI is an end view of one of the carriers.

Fig. VII is a fragmentary, top plan view 70 of one of the carriers showing one form of clamping means.

Fig. VIII is a fragmentary, sectional view taken on the line 8—8 of Fig. VII.

Fig. IX is a detail, sectional view taken 75 on the line 9—9 of Fig. VII.

Fig. X is a detail, sectional view taken on the line 10—10 of Fig. VII.

Fig. XI is a detail perspective view of 80 the rock arm.

Fig. XII is a top plan view of one of the carriers showing another form of clamping means.

Fig. XIII is a bottom plan view of the 85 carrier shown in Fig. XII.

Fig. XIV is a fragmentary view of the carrier in side elevation.

Fig. XV is an enlarged, detail, sectional view taken on the line 15—15 of Figs. XII 90 and XIII.

In the drawings, similar reference numerals indicate similar parts throughout the several views, and the sectional views are taken looking in the direction of the 95 little arrows at the ends of the section lines.

Considering the numbered parts of the drawing, my invention comprises a rack which is adapted to be supported on the wall and to carry a plurality of independently 100 removable carriers in which the prints, drawings or sheets to be filed are clamped. The brackets 20 are fastened to the wall 21 by the screws 22. The bar 25, which is here shown as of square, tubular construction, has 105 a head 23 disposed between the brackets 20

and carrying the pins 24 which are journaled in the brackets 20. These pins 24 being thus journaled permit the bar 25 to swing in a horizontal plane. The hollow bar 26 which is of slightly greater cross section than the bar 25 is slidably mounted upon said bar 25. This bar 26 carries the end plates 28 which are preferably of sheet metal stamped to the proper form. These 10 end plates are tapered so that the lower end thereof is narrower than the top and are provided with a plurality of downwardly inclined slots at the sides thereof, the inner end of each slot being offset inwardly with 15 reference to the slot above. The ears 30 are provided on the upper corners of the end plate and are bent parallel to the plate so that they may be used to hold a card carrying data referring to the drawings filed in 20 the rack. The ear 31 is stamped out from the body of the end plate to serve as a finger grip in moving the rack on the bar 25.

This rack is designed to carry a plurality of independently removable carriers in 25 which the sheets to be filed can be clamped or bound. The rack shown in the drawings will carry six of these carriers and its capacity can be increased by providing end plates having additional slots. Each carrier comprises a bar 32, approximately as 30 long as the rack, having the portions 33 turned downwardly at the corners thereof to serve as legs for supporting the carrier when taken out of the rack and laid on a 35 table in order to examine the drawings therein. A portion 34 at each end of the bar 32 is twisted so as to lie in a plane at an angle to the plane of the bar 32 and serve as pins for supporting the carrier in the rack. 40 The angle at which these pins 34 are twisted is such that, when they are inserted in the slots 29, the carrier will lie in a vertical plane. The portions 34 being flat they prevent turning or twisting of the carrier when 45 in place in the rack. At one end of the bar 32 there is provided the block 35 having an undercut, inclined face 36. A clamping plate 37, which is slightly narrower than the bar 32, has one end thereof inserted beneath 50 the inclined face 36 of the block 35 and when said clamping plate is forced against the bar 32 by suitable clamping or locking means the sheets are securely bound in the carrier. The plate 37 is shorter than bar 32 55 for a purpose which will be set forth hereinafter.

In Figs. VII to XI inclusive, I have shown one form of clamping means. In this form, straps 38 are secured to the bottom 60 face of the bar 32 and carry bearing blocks 39 in which one arm 40 of a rock arm has a bearing. Each of these bearing blocks has a curved slot 42 and the pin 41 carried by the arm 40 is disposed in said slot. The 65 rock arm has a portion 43 extending at right

angles to the arm 40 and an arm 44 extending at right angles to the portion 43 and the arm 40. The arm 40 when in position in the bearing block 39 lies parallel to the bar 32 while the arm 44 extends over the clamping plate 37. A pin 45 is carried by the end of each arm 44 and a lever 46 is fulcrumed on each of said pins 45, each of said levers being provided, at one end, with the nose 47 adapted to engage the upper surface 75 of the clamping plate 37. The inner ends of the levers 46 are connected by the link 48, the ends of which are pivotally connected to the inner ends of the levers 46 by the pins 49. A screw 50, having the head 51, is 80 threaded through the link 48 and the end of said screw engages the upper surface of the clamping plate 37.

In Figs. XII to XV inclusive, I have shown another form of clamping means which, in some cases, is to be preferred to the form above described in that it requires less space. The blocks 52 are secured to the lower surface of the bar 32 and the shaft 53 is journaled in said blocks. The worms 54 90 are fixed on the shaft 53 and said shaft is provided with the head 55 by means of which it may be rotated. Blocks 56 are secured to the upper surface of the bar 32 and a stub shaft 57 is journaled in each of said 95 blocks 56 and extends through the bar 32 carrying on its lower end, beneath the bar 32, a gear 58 meshing with the worm 54. Wiper arms 59 are fixed to the upper ends 100 of the shafts 57 and wedges 60 are provided on the upper surface of the clamping plate so that the wiping arms 59 will engage said wedges as the shaft 57 is rotated so as to force the clamping plate 37 toward the bar 32. I have indicated the sheets bound in the 105 carrier by the reference character A.

From the description of the parts given above, the operation of my device should be very readily understood. As pointed out above, the bar 25 is so mounted in the 110 brackets 20 that it may be swung in a horizontal plane so that the rack may be swung against the wall to economize space and moved to a position at right angles to the wall when it is desired to remove drawings 115 from the rack. The rack proper consists of the hollow bar 26 carrying the end plates 28 and the rack can be moved away from the wall by sliding the hollow bar 26 on the bar 25. The end plates of the rack have the 120 inclined slots 29 which receive the pins 34 at the ends of the carrier. As already pointed out, the pins 34 are flat and lie in a plane at an angle to the plane of the carrier so that the carrier will lie in a vertical 125 plane when mounted in the rack. The clamping plate 37 is shorter than the bar 32 of the carrier so that the upper right hand corners of the drawings or sheets bound in the carrier are free and one may examine 130

data on the sheets at this point without removing the sheets from the carrier. These carriers are independently removable from the rack and drawings or prints may be grouped or classified by filing all the prints of one group or class in a single carrier. If the drawings in this group are to be examined, the carrier can be removed from the rack without disturbing the other carriers.

10 The slots 29 are so arranged that the sheets in the carrier carried by the upper slots will lie in front of the sheets carried by the other carriers so that any carrier can be removed without removing the others. The carrier 15 when removed can be laid flat on a table being supported by the legs 33.

The sheets are bound in the carrier between the clamping plate 37 and the bar 32 and means are provided for firmly forcing the clamping plate against the sheets to bind them against the bar. This clamping means is of such a nature that it will exert a considerable pressure on the clamping plate and will lock it positively but will, 25 at the same time, be quickly releasable. In Figs. VII to XI inclusive, I have shown one form of clamping and locking means, while, in Figs. XII to XV inclusive, I have shown another form of clamping and locking 30 means which I prefer to employ in some cases.

In the form shown in Figs. VII to XI, as the operator turns the screw 50 the end thereof will bear against the clamping plate 37 and will force the link 48 away from plate 37. Said link 48 is connected to the ends of levers 46, which are fulcrumed on the pins 45, so that the nose 47 of each lever bears down on the clamping plate 37. As a 40 result, when the screw 50 is turned, pressure is applied to the clamping plate at three separate points. The levers 46 are carried so that they may be swung back away from the clamping plate 37 since the pins 45 are carried by the ends of the arms 44 of the rock arm. The movement of each of the rock arms is limited by the pin 41 disposed in the curved slot 42 so that an initial longitudinal movement of the rock arm is required. This longitudinal movement is impossible when the screw 50 is turned down to apply pressure to the clamping plate but, 50 when the pressure is released, the rock arms can be rotated, with the pins 41 working in slots 42 and guiding the movement of the rock arms, so as to swing back the clamping means from above the clamping plate.

In the form shown in Figs. XII to XV inclusive, the clamping plate 37 is forced toward the bar 32, to bind the sheet in the carrier, by the engagement of the wiper arms 59 with the wedges fixed on the upper surface of the clamping plate. The shaft 53 carries the worms 54 and, as it is rotated, 65 the stub shafts 57 are rotated through the

gears 58 meshing with the worms. The rotation of each stub shaft causes the wiper arm 59 to move over the inclined surface of the wedge 60 forcing the clamping plate against the sheets. By turning the shaft 53 70 in the reverse direction, the wiper arms will be moved from over the clamping plate so that the latter can be freely removed.

I am aware that the embodiment of my invention, here shown and described, can be 75 varied considerably without departing from the spirit of my invention and, hence, I desire to claim my invention broadly as indicated by the appended claims. I have found this particular embodiment, however, to be 80 desirable from many standpoints and, therefore, I wish to claim it specifically as well as broadly.

Having thus described my invention, what I claim as new, and desire to secure by 85 Letters Patent is:

1. A device of the class described comprising a bracket; a bar mounted in said bracket so as to swing in a horizontal plane; a tube slidably mounted on said bar; plates secured 90 to the ends of said tube, said plates being provided with a plurality of slots extending inwardly and downwardly from the edges thereof; the inner ends of each pair of slots being nearer the center of said plate than 95 the ends of the slot above; and a plurality of independently removable sheet carriers, each carrier comprising a flat bar having legs at the four corners thereof and a portion extending from each end thereof, twisted 100 to line in a plane at an angle to the plane of the bar and adapted to be disposed in one of said slots, a clamping plate shorter and narrower than said bar, and means for clamping a plurality of sheets between said 105 plate and said bar.

2. A device of the class described comprising a bracket; a bar mounted in said bracket to swing in a horizontal plane; a tube slidably mounted on said bar; plates 110 secured to the ends of said tube, said plates being provided with a plurality of slots extending inwardly and downwardly from the edges thereof, the inner ends of each pair of slots being nearer the center of said 115 plate than the ends of the slots above; and a plurality of independently removable sheet carriers, each carrier comprising a flat bar having a portion, extending from each end, twisted to line in a plane at an angle 120 to the plane of the bar and adapted to lie in one of said slots, a clamping plate shorter than said bar, and means for clamping a plurality of sheets between said plate and said bar.

3. A device of the class described comprising a bracket; a bar mounted in said bracket to swing in a horizontal plane; a tube slidably mounted on said bar; plates secured to the ends of said tube, said plates 130

being provided with a plurality of slots extending downwardly and inwardly from the edges thereof, the inner ends of each pair of slots being nearer the center of said plate than the ends of the slots above; and a plurality of independently removable sheet carriers, each carrier comprising a flat bar, provided with portions adapted to lie in said slots and to support the carrier in a vertical plane, a clamping plate, and means for clamping a plurality of sheets between said plate and said bar.

4. A device of the class described comprising a bracket; a bar mounted to swing in a horizontal plane; a tube slidably mounted on said bar; plates secured to the ends of said tube, said plates being provided with a plurality of slots extending inwardly and downwardly from the edges thereof, the inner end of each pair of slots being nearer the center of said plate than the ends of the slots above; and a plurality of independently removable sheet carriers, each carrier having supporting means adapted to be disposed in said slots.

5. A device of the class described comprising a bracket; a bar mounted to swing in a horizontal plane, and a rack slidably mounted on said bar and adapted to receive, and support in a vertical plane, a plurality of independently removable sheet carriers.

6. A device of the class described comprising a bar mounted to swing in a horizontal plane, and a rack slidably mounted on said bar and adapted to receive a plurality of independently removable sheet carriers.

7. A device of the class described comprising a bar; plates secured to the ends of said bar, said plates being provided with a plurality of slots extending inwardly and downwardly from the edges thereof; and a plurality of independently removable sheet carriers having portions, twisted to lie in a plane at an angle to the plane of the carrier, and adapted to lie in said slots and support said carrier in a vertical plane.

8. A device of the class described comprising a bar; a bar slidably mounted thereon; plates secured to the ends of said last named bar and adapted to support a plurality of independently removable sheet carriers in a vertical plane.

9. A device of the class described comprising the combination of a base plate, having downturned portions at the four corners forming supporting legs; a block secured to one end of said base plate and having an undercut inclined face; a clamping plate disposed above said base plate with one end abutting the inclined face of said block, said plate being shorter and narrower than said base plate; a pair of journal blocks carried by said base adjacent the rear edge thereof, each journal block hav-

ing a curved slot; a rock arm journaled in each block and having a pin disposed in said slot, said rock arms having portions extending at right angles to said journal block over said clamping plate; a lever fulcrumed on the end of said last named portion of the rock arm, each lever having a nose adapted to engage the clamping plate; a link connecting the adjacent ends of said levers; and a screw extending through and having a screw-threaded engagement with said link, the end of said screw engaging said clamping plate.

10. A device of the class described comprising the combination of a base plate; a block secured to one end of said base plate and having an undercut inclined face; a clamping plate disposed above said base with one end abutting the inclined face of said block; a pair of journal blocks carried by said base plate adjacent the rear edge thereof, each of said blocks having a curved slot; a rock arm journaled in each block, having a pin disposed in said slot and limiting the movement of said rock arm, each rock arm having an arm extending forwardly above said clamping plate; a lever fulcrumed on the end of each of said arms, and having a nose adapted to engage the clamping plate; a link connecting the adjacent ends of said levers, and a screw threaded through said link and abutting the clamping plate.

11. A device of the class described comprising the combination of a base plate; a clamping plate; a pair of journal blocks carried by said base plate adjacent the rear edge thereof; each of said blocks having a curved slot; a rock arm journaled in each block, having a pin disposed in said slot and limiting the movement of said rock arm, each rock arm having an arm extending forwardly above said clamping plate; a lever fulcrumed on the end of each of said arms and adapted to engage the clamping plate; a link connecting the adjacent ends of said levers; and a screw threaded through said link and engaging the clamping plate.

12. A device of the class described comprising the combination of a base plate; a clamping plate; a pair of rock arms journaled adjacent the rear edge of said base plate, each of said rock arms having an arm extending forwardly over said clamping plate, said rock arms being rotatable to swing said forwardly extending arms from above the clamping plate after a preliminary longitudinal movement of said rock arms; a lever fulcrumed on the end of each of said forwardly extending arms and adapted to engage the clamping plate; a link connecting the adjacent ends of said levers; and a screw threaded through said link and engaging said clamping plate.

13. A device of the class described com-

30

35

40

45

50

prising the combination of a base plate; a clamping plate; a pair of rock arms each having an arm extending forwardly over said clamping plate, said rock arms having a limited rotatable movement whereby the forwardly extending arms can be moved from above the clamping plate after a preliminary longitudinal movement of the rock arms; a lever fulcrumed on the end of each 10 of said forwardly extending arms; and means for actuating said levers to apply pressure to the clamping plate.

14. A device of the class described comprising a base plate; a clamping plate; a 15 pair of fulcrums; a lever pivoted on each fulcrum; and means for actuating said levers to apply pressure to said clamping plate; said fulcrums being movable from above the clamping plate after a preliminary 20 movement longitudinally thereof.

15. A device of the class described comprising the combination of a base plate; a clamping plate; a pair of movable fulcrums normally disposed above the clamping 25 plate; a lever pivoted on each fulcrum; and means for actuating said levers to apply pressure to the clamping plate; said fulcrums being shiftable from above the clamp-

ing plate when the pressure thereon is relieved.

16. A device of the class described comprising the combination of a base plate; a clamping plate; means, normally disposed above said clamping plate, for applying pressure thereto, and means for quickly shifting said pressure applying means from above the clamping plate to permit of the ready removal of the latter.

17. A device of the class described comprising the combination of a base plate; a 40 block, having an undercut inclined face, carried by said base plate; a clamping plate, shorter than said base plate, disposed with one end abutting the undercut face of said block; and means for applying pressure to 45 said clamping plate.

18. A device of the class described comprising the combination of a base plate; a block, having an undercut inclined face, carried by said base plate; a clamping plate 50 disposed with one end abutting the undercut face of said block; and means for applying pressure to said clamping plate.

In witness whereof, I have hereunto set my hand.

JOHN J. HASSELBACH.
